SAFETY RAZOR

John Edwin Fisk, South Euclid, Ohio

Application October 13, 1944, Serial No. 558,541

5 Claims. (Cl. 30—32)

1

The principal object of this invention is to provide a double edge safety razor which is sufficiently inexpensive so that its value to the consumer will more than offset its cost if the consumer uses the razor only once or a very few times.

Another object is to provide such a razor having a head provided with a cylindrically convex surface arranged to carry a blade, and an effective means to bend the blade to make it conform substantially to the convexity of the head or at least to impart to the blade a sufficient arch to impart thereto adequate rigidity for use in shaving and further to present the razor edge at the necessary or desired shaving angle.

Another object is to provide a safety razor frame, principal portions of which are made from sheet material and which present substantially flat surfaces adapted to be printed upon in order to enable economical application and effective display of advertising matter.

A further object is to provide a safety razor of relatively inexpensive, inherently flexible material such as paper, fibre, sheet plastic or wood so constructed as to have the necessary rigidity required for shaving.

Still another object is to provide a permanently assembled safety razor blade and frame or holder which assembly can be easily and adequately cleansed by flushing with water at average tap or faucet pressure.

Other objects and features will become apparent from the following description of the illustrative forms of razor shown in the drawings in which:

Fig. 1 is a front or rear view of the preferred form of razor in accordance herewith;

Fig. 2 is a side view of the razor of Fig. 1;

Fig. 3 is a top or plan view of the same form of razor with portions of the head and blade broken away to show more clearly the relationship of the parts;

Fig. 4 is a fragmentary sectional view taken along line 4—4 in Fig. 2;

Fig. 5 is a front or rear view of a modified form of razor employing the principles of this invention;

Fig. 6 is a top or plan view of the razor according to Fig. 5 with portions broken away;

Figs. 7 and 8 are sectional views taken along lines 7—7 and 8—8, respectively, of Fig. 5;

Fig. 9 is a perspective view of a modified form of retainer or clip used for bending the blade and holding it in place;

Fig. 10 is a fragmentary front or rear view of

2

the razor with the clip of Fig. 9 in operative position thereon;

Figs. 11 and 12 are views similar to Figs. 9 and 10, respectively, showing a modified blade retaining and bending clip.

Generally, Figs. 1, 2, 3 and 4 show the preferred form of the razor. Figs. 5 to 12, inclusive show variations retaining the principal features of the preferred form and modified only in respect to the means for positioning and bending the blade and holding the parts assembled.

The razor as shown in all assembly views comprises a rigid head 10, made preferably of water repellent sheet material such as highly compressed paper or similar fibre stock substantially the length and width of the most commonly used two edged razor blade shown at 13, said head having end portions 12 of reduced width, for example the width of the smaller end portions 13' of the blade. The shape of the head 10, in plan view, is approximately that of the razor blade which the head underlies and supports, being approximately coextensive therewith as shown by comparison of Figs. 1 to 4. The blade supporting surface of the head is preferably cylindrically convex and has alternate transverse ribs and grooves 14 and 14', respectively, extending the full width of the head. The grooves 14' form with the blade, when the blade is in operating position on the head, ducts which are open at both ends.

The ribs 14 and grooves 14' may be formed by corrugating sheet stock from which the head 10 may be economically made—for example pressed and/or rolled to form the ribs and grooves and the cylindrical convexity either before or after cutting of the stock to the desired head shape. The reduced width end portions 12 of the head underlying the blade portions 13 are not ribbed or corrugated. Since only the tops of the ribs have to make supporting contact with the blade, the major portion of the under surface of the blade (crosswise from cutting edge to cutting edge) is wholly out of contact with the head. Thus cleansing of the razor after use requires only an easily performed flushing operation as under a water tap or in a bowl containing water since the ducts provided by the grooves 14' are unrestricted from end to end as well as open at both ends. The limited area of contact between the main or central portion of the blade and the head may be even more pronounced than as illustrated, as by modifying the ribs so that they make substantially only line contact with the blade, thus increasing the effective size of the

ducts for flushing purposes without having to alter the distance between centers of the ducts. The top margins of the head underlying the two cutting edges of the blade are preferably beveled or chamfered as at 10a.

A strip of comparatively flexible sheet material 15 of less thickness than the head surmounts the blade and head. This strip can be of approximately the width of the smaller end portions 13' of the blade and cover the central portion of the blade for its entire length leaving both cutting edges of the blade exposed. Portions 16 of the strip 15 are bent around the ends of the blade and head and are brought together as at 17 on the side of the head opposite the blade in symmetrical arrangement to form a handle disposed centrally of the head. Extensions 18 of the strip portions 16 thus brought together may be fastened in mutually overlapping relationship by suitable fastening means such as staples 19.

The strip 15 if of paper or fiber stock, as preferred, can be readily imprinted by ordinary methods and the portion of the strip which overlies the blade and both exposed faces of the handle portions 16 and 18 may thus carry and effectively display advertising matter without greatly increasing the cost of the razor.

Wire clips or staples 20 at least partially encircling (e. g. bent around) the smaller end portions of the blade and head are provided to hold the head 10, blade 13 and strip 15 in assembled condition. Such wire clips 20 also form the principal means for bending the blade to make it conform generally to the convex side of the head constituted by the top surfaces of the ribs.

The blade, head and strip 15 can also be held together by wire clips extending longitudinally of the head. Such a method is disclosed in the modified form of razor shown in Figs. 5, 6 and 7 wherein clips 26 extend over the blade parallel to the cutting edges, over the ends of the blade and through the head, holding the strip, blade and head together in the manner of a paper staple. The strip 15 used in this form has a somewhat wider portion 27 where it overlies the wider part of the blade so that the strip can underlie and be bound by the clips 26. Additional unclinched staples 27 are preferably used to insure firm fastening of the strip 15 to the ends of the head 10. The portions 16 and 18 of the strip 15 forming the handle may be formed to constitute matching longitudinal channels as shown in Fig. 8 which, when brought together and fastened as by pairs of clinched staples 28, afford greater rigidity to the handle because the handle so formed is tubular. If the stock of the strip 15 is inherently sufficiently stiff (e. g. paper tempered by pressing or impregnation with suitable plastic etc.) the strip will serve to hold the blade in curved form without assistance by the fasteners as at 20, Figs. 1 to 4, or 26, Figs. 6 to 8. The fasteners could then be further simplified and perhaps omitted from the head parts of the razor within the proper scope of the present invention.

Caps as shown in Figs. 9 and 11 preferably of thin sheet metal can effectively be used instead of the wire clips to hold the blade in curved condition and to hold the head parts together. The cap 30 shown in Fig. 9 has side extensions 31 at each of its four corners which may be bent inwardly in pairs to embrace the strip 15, blade 13 and head 10 as shown in Fig. 10. The cap, in transverse cross section, generally conforms to

the convexity of the head so as to maintain the desired curvature of the blade.

The cap 40 shown in Fig. 11 has its ends 41 bent toward each other to secure the head, blade and strip 15 together as shown in Fig. 12.

The head member 10 of Figs. 5 to 7, 10, 12, is especially adapted to be made of hard or comparatively rigid material, for instance wood or inexpensive plastic or fiber stock. The ribs and grooves 14 and 14', respectively, would in those forms be made by cutting, molding or pressing, whichever is found most appropriate; and the valleys between the ribs could in any case be straight, as shown; or, in other words, not curved to conform to the tops of the blade supporting ribs or ridges.

The term "wire" as used herein does not necessarily mean that the same is circular in cross section. Several of the principles herein explained are practically applicable to safety razors of conventional or continuing use type wherefore the invention is not to be considered confined wholly to an economically dispensable or limited use razor although the illustrated forms are designed principally with that specific market in view.

I claim:

1. A safety razor comprising a head, a blade and a strip of comparatively flexible material of approximately uniform width and thickness narrower in width than the blade, surmounting the blade and head, the ends of said strip of material extending around and intimately under the longitudinal ends of the blade and head, and forming a juncture approximately centrally beneath the head and extending downwardly beyond the juncture to form a handle for the razor.
2. A safety razor comprising a head, a two-edged blade and a strip surmounting the blade and head, the ends of the strip extending around the longitudinal ends of the blade and head and means including a wire clip looped about portions of the head, blade and strip and binding said parts permanently together.
3. A safety razor comprising a head having a convex blade supporting surface, a two-edged blade and a strip of material extending the full length of the blade overlapping the ends of the blade and head, a cap substantially rectangular in shape surmounting the strip, head and blade, said cap having extensions adjacent each end permanently bent to closely underlie the head and cause the blade and strip to conform to the convexity of the head while binding the strip, head and blade permanently together, the ends of said strip extending below the head to serve as a handle for the razor.

4. A safety razor comprising a comparatively rigid head having a generally convex top surface, a comparatively flexible double edged blade overlying said surface, a handle formed of a single strip of sheet material having an upper portion parallel to the head and lying adjacent thereto and two lower portions parallel to the head and marginally overlapping it, and fastening means securing the blade, head and said upper and respective lower portions of the strip together, said fastening means acting on said upper portion of the strip in a manner to cause the blade to conform substantially to the convexity of said surface of the head.

5. An economically disposable safety razor comprising a transversely arched, relatively rigid, supporting plate for a blade and a blade securing strip of flexible, readily bendable material over-

lying the plate and secured to both ends of the plate and operative to hold a conventional flexible blade against the plate and cause the blade to conform generally to the arched top of the plate, the ends of the strip projecting beyond the securing means, extending toward each other beneath the plate and joined together therebelow to enable use thereof as a handle.
